UNITED STATES PATENT OFFICE.

WILLIAM N. BELL, OF NATIONAL MILITARY HOME, CANTON.

PROPELLER FOR BOATS.

1,111,988.

Specification of Letters Patent. Patented Sept. 29, 1913.

Application filed November 17, 1913. Serial No. 801,242.

To all whom it may concern:

Be it known that I, WILLIAM N. BELL, a citizen of the United States, residing at National Military Home, in the county of 5 Montgomery and State of Ohio, have invented certain new and useful Improvements in Propellers for Boats; and I do declare the following to be a full, clear, and exact description of the invention, such 10 as will enable others skilled in the art to which it appertains to make and use the same, reference being had to the accompanying drawings, and to the letters and figures of reference marked thereon, which form a 15 part of this specification.

This invention relates to new and useful improvements in propelling means for boats.

The object of the invention is to provide a device of this type which is simple in 20 construction and in which a maximum amount of the power is generated by the driving engine or motor and is utilized in propelling the boat, and a considerable saving in power is accomplished as hereinafter 25 described and claimed.

Referring to the accompanying drawings, Figure 1 is a top plan view of a boat equipped 30 with my improved propelling means; Fig. 2 is a bottom plan view of the same; Fig. 3 is a section on the line *a—a* of Fig. 1; Fig. 4 is a section on the line *b—b* of Fig. 1; and Fig. 5 is a section on the line *c—c* of Fig. 1.

In the specification and drawings, similar reference characters indicate corresponding parts.

The hull of the boat consists of a bottom 1, sides 2, and an inclined rear end 3 which is sufficiently removed from the end of the boat to provide an inclosed space for the 40 location of the propellers. Mounted in the interior of said boat on the bottom thereof may be any well known form of prime mover such as an explosive engine 4. The said engine 4 is provided with a shaft 5 which extends through a suitable bearing 6 in the rear end of the boat. The end of the shaft 5 opposite the engine is supported by a bearing 7 which projects from the rear end of the boat. Mounted on the extreme 50 end of the shaft 5 is a screw propeller 8 which lies below the water line and consequently revolves in the water which arises between the sides and under the rear end of the boat. In addition to the screw propeller 8, the boat is provided with right 55 and left paddle wheels 9 which are attached to a shaft 10 journaled in bearings 11 in the sides of the boat. The said paddle wheels 9 are driven from the screw propeller 8 through the agency of an impact 60 wheel 12 mounted on and attached to the shaft 10 between the paddle wheels 9. The positions of the screw propeller 8 and the impact wheel 12 are such that the vanes of the impact wheel are, when on their lower 65 run, in a position to receive the impact of the water thrown rearwardly by the propeller 8 thereby rotating the impact wheel 12 and consequently the paddle wheels 9. To more effectually direct the water thrown 70 back by the propeller 8, against the vanes of the impact wheel, the said propeller 8 and the lower run of the impact wheel are mounted in a tunnel which is inclosed by sides 13, bottom 14 and top 15. The sides 75 13 and the bottom 14 separate the propeller 8 and the impact wheel 12 from the water acted upon by the paddle wheels 9. By this arrangement of the screw-propeller 8, impact wheel 12 and paddle-wheels 9, what- 80 ever power is lost by the propeller in throwing the water rearwardly is recovered by the impact wheel 12. The paddle-wheels will develop a certain amount of power themselves due to the irregularities in the 85 current of water flowing by the paddle-wheels. This power is utilized by the following device. Mounted on the shaft 10 is a sprocket 16 around which passes a chain 17. The chain 17 extends forwardly over 90 and through a suitable opening in the rear end 3 of the boat above the water line, to a sprocket 18. The chain 17 may be guided by rollers 19. The sprocket 18 is mounted on a shaft 21 journaled in a bearing 22. 95 Also mounted on the shaft 21 is a bevel gear 23 in mesh with a bevel gear 24 on the shaft 5, and through which the power generated by the paddle-wheels is delivered to the shaft to be expended usefully by the 100 propeller 8. The sprocket chain 17 is also instrumental in driving the paddle-wheels 9, if for any reason, the propeller 8 should become inoperative. Means are also provided for driving from the shaft 10 any 105 auxiliary devices such as a dynamo or bilge pump, and which consists of a drive pulley 25, sprocket chain 26 similar to the sprocket chain 17, and a sprocket 27 mounted on the shaft 10.

While in the drawings, I have shown my improved propeller as applied to a simple

form of flat bottom boat, it is to be understood that this simplified hull is shown merely for the purpose of illustration only, and that the invention is adaptable to any 5 well known form of hull.

Having described my invention, what I claim and desire to secure by Letters Patent is:

10 In a propelling means for boats, the combination with the hull of a boat the stern of which is provided with an inclosed centrally disposed space open to the water at its forward and rearward ends, of a screw propeller mounted in the forward portion 15 of said inclosed space, an impact wheel

mounted within said inclosed space rearwardly of said propeller, and paddle wheels mounted on opposite sides of said inclosed space, said paddle wheels and impact wheels being fixed to a common shaft, and gearing 20 by means of which the shaft of the propeller is connected to the common shaft of the impact and paddle wheels.

In testimony whereof I affix my signature in presence of two witnesses.

WILLIAM N. BELL.
